UNITED STATES PATENT OFFICE.

WALLACE M. GRAY, OF CINCINNATI, OHIO.

LOCOMOTIVE WATER-COLUMN.

1,177,512.

Specification of Letters Patent. Patented Mar. 28, 1916.

Application filed July 6, 1915. Serial No. 38,219.

To all whom it may concern:

Be it known that I, WALLACE M. GRAY, a citizen of the United States, residing at Cincinnati, in the county of Hamilton and State of Ohio, have invented certain new and useful Improvements in Locomotive Water-Columns, of which the following is a specification.

My invention relates to improvements in locomotive water columns. One of its objects is to provide a column to be located between two railway tracks and adjustable to supply water to locomotive tenders on either track.

Another object is to provide improved means to support and adjust the spout, to hold it in idle position to prevent it becoming inoperative in freezing weather, to provide for a smooth flow of water without leakage, and to provide those vertical and lateral adjustments required in practice to reach the inlet port of the tenders to be supplied with water.

Another object is to provide an improved, simple and inexpensive apparatus.

My invention also comprises certain details of form, combination, and arrangement, all of which will be fully set forth in the description of the accompanying drawings, in which:

Figure 1 is a side elevation of the upper portion of a water column embodying my improvements. Fig. 2 is a front elevation of a column illustrating its adjustment to supply water over tracks at either side. Fig. 3 is a top plan view of Fig. 1. Fig. 4 is a perspective view of the upper portion of the column with the spout detached. Fig. 5 is a perspective view of the spout carrying swivel block detached. Fig. 6 is a perspective view of the spout detached.

The accompanying drawings represent the preferred embodiment of my invention in which—

45 A represents the stationary vertical section of the water column and A' represents a downwardly directed exit or return bend, either integral with or rigidly attached to said vertical column.

50 The base of the vertical column is mounted upon a suitable concrete base either at the side of a single railway track or between two railway tracks B and B' as indicated in Fig.

55 2. A valve of the usual type is located beneath the ground and is actuated by means of a valve rod 2 carried by the column A,

Water is conducted from the open end of the return bend A' to the receiving port of the water tank of a locomotive tender by means of an adjustable spout D. It is desirable that this spout should be adjustable to deliver water to tenders on tracks at either side of the column, also that it should be adjustable at its extended end to reach the receiving port of a variety of old style and new style locomotives of various dimensions also that it should be adjustable laterally within certain limits, since it is difficult to bring locomotives to a stop always directly beneath a given point. It is also desirable that the water should flow readily through the spout and should not back up therein or leak therefrom, and further that in cold or freezing weather the spout should drain freely and not be rendered inoperative from accumulation of ice thereon. All of these requirements are fulfilled by my improved apparatus.

The spout D is preferably supported from above by means of a bar or lever E which is counter balanced by means of weights 3 and is mounted respectively upon a vertical axis 4 and a horizontal axis 5 so as to have a universal joint movement. A shackle or block F has a slightly inclined rib 6 on its under face which seats in a counterpart groove or channel in the upper face of the bracket 7, which is mounted upon or formed integral with the return bend A and preferably vertically above the column exit. The stud shaft 4 carried by the shackle F projects downwardly through a vertical opening in the bracket 7 to constitute the vertical axis on which the bar E turns, and is provided with lock nuts 8 to prevent disengagement from the bracket, while the inclined rib 6 in connection with the groove in the upper face of the bracket tends to guide and hold, or lock the bar E in its idle position parallel to the track, and prevent its accidental displacement to a position in the way of passing trains. The counterweights 3 on the bar E have a short radius of movement so as not to be in the way of passing trains on either track at any time. The shackle F has upwardly projecting ears 10 which support the horizontal axis or bolt 5 upon which the bar E pivots for its movement in a vertical plane.

The spout D which is of light sheet metal has an oval or elongated inlet end which is preferably larger than its exit end, and

which telescopes over the exit end of the column with a free air space between. The spout is provided with eyes 14 and 15 which are connected by links or chains 16 and 17 to eyes 18 and 19 carried by the bar E, thus suspending the spout from bar E in such position that its inlet end is movable relative to the exit end of the column, but can not in its normal movements be disengaged therefrom while the exit end of the spout has a wide range of adjustment vertically horizontally and laterally to enable the exit end of the spout to be introduced into the tank opening of a tender either to the right or left of the column. Changes in the position of eye 19 on the bar E serve to increase or decrease the movement of the inlet end of the spout relative to the column.

20 A handle 20 at the free end of bar E enables a locomotive fireman to reach said handle from a tender in the usual manner and swing the bar E over the tender and then depress the bar E and introduce the spout exit into the tender tank opening. A pull on the hand chain 21 then serves to lift the valve rod 2 and furnish a supply of water through the column and spout.

In order that the spout may have a considerable range of adjustment, and be free from leakage at the joints, and not subject to accumulation of ice, the inlet end of the spout is of relatively greater diameter than the exit end of the column, and is preferably oval or elongated. Thus the inlet of the spout has both an endwise and a lateral movement relative to the exit end of column, and also there is a free air space practically entirely around the exit of the column and between it and the receiving end of the spout. This air space in addition to providing for telescopic and lateral adjustment of the spout also enables a liberal supply of air to enter between the column and spout and to mingle with the water passing down the spout, thereby preventing any tendency for water to flow out or leak at the open joint between the column and spout. This open joint also tends to quickly drain the water from the spout as soon as it is out of use, and prevents the accumulation of ice, or the spout being rendered inoperative by accumulation of ice thereon. Any adjustment at the joint between the spout and column, either vertical or lateral is greatly magnified at the free end of the spout, thus affording the free end of the spout an ample range of adjustment in any direction required to connect with the receiving port of a tender either old or new style, whether the tender port is brought to a stop directly opposite the column or not.

The valve rod may be operated in any manner desired. I preferably connect a light hand or pull chain 21 at one end to

the link 16 and at the other end over a pulley 25 to the valve rod 2 so that after the spout is in position the operator may pull the chain 21 and open the valve as indicated in Figs. 1 and 2.

The apparatus herein illustrated and described is capable of considerable modification without departing from the principle of my invention.

Having described my invention what I claim is:

1. A locomotive water column comprising a rigid substantially vertical column having a stationary downwardly directed exit nozzle, a spout telescoped at its receiving end loosely over said nozzle and movable relative to said column in vertical and horizontal planes while preserving said telescopic relation with the nozzle, and means to support said spout in substantial equilibrium from said column.

2. A locomotive water column comprising a stationary substantially vertical column having a downwardly directed exit nozzle, a spout telescoping at its receiving end loosely over said nozzle and movable relative to said column in vertical and horizontal planes while preserving said telescopic relation with the nozzle, and means pivotally supported from said column at a point substantially vertically above the exit of said nozzle to support said spout in substantial equilibrium from said column.

3. A locomotive water column comprising a stationary substantially vertical column having a stationary supported downwardly directed exit nozzle, a spout having an elongated opening at its receiving end telescoping loosely over said nozzle and movable relative to said column in vertical and horizontal planes while preserving said telescopic relation with the nozzle, and means to support said spout in substantial equilibrium relative to said column.

4. A locomotive water column comprising a substantially vertical column having a downwardly directed exit nozzle at its upper end, an adjustable supporting member carried by said column, and a spout having a receiving end larger than and telescoping over the nozzle of said column with a free air space between the column and inside of the spout, said spout being supported in position by said supporting member and adjustable therewith to different horizontal and vertical positions while preserving said telescopic relation with the nozzle.

5. A locomotive water column comprising a stationary substantially vertical column to be mounted between two railway tracks and having a downwardly directed exit nozzle in a plane relative to said column substantially parallel to said tracks, a supporting member mounted upon said column and adjustable in horizontal and vertical planes relative

- thereto, and a spout having a receiving end larger than and telescoping over the nozzle of said column with a free air space between the column and inside of the spout, 5 said spout being supported in position by said supporting member and adjustable therewith to different horizontal and vertical positions while preserving said telescopic relation with the nozzle.
- 10 6. A locomotive water column comprising a substantially vertical column to be mounted between two railway tracks and having a downwardly directed exit nozzle over the space between the tracks, a supporting member 15 pivotally mounted upon said column and adjustable relative thereto in horizontal and vertical planes, and a spout having a receiving end larger than and telescopically movable over the downwardly directed nozzle of said column with a free air space between said spout and nozzle, said spout being supported in position by and adjustable with said supporting member, and means to retain said spout in its idle position out of 20 the way of passing trains except when required for use.
7. A locomotive water column comprising a stationary substantially vertical column having a downwardly directed exit nozzle, 30 a supporting member pivotally mounted upon said column at a point substantially above said nozzle and adjustable in vertical and horizontal planes relative to said column, and a spout carried by and movable 35 with said supporting member, the receiving end of said spout telescoping loosely over said nozzle.
8. A locomotive water column comprising a substantially vertical column to be mounted 40 at the side of a railway track and having a valve rod and a downwardly directed exit nozzle in a plane substantially parallel to the track relative to said column, an adjustable supporting member mounted upon 45 and having horizontal and vertical movement relative to said column, a spout carried by and movable with said supporting member with its inlet and telescopically engaging over said exit nozzle, means to counterbalance said spout and its supporting member, and means to normally retain said spout and its supporting member in idle position substantially parallel to the track. 50
9. A locomotive water column comprising
- a substantially vertical column to be mounted between two tracks and having a downwardly directed exit nozzle over the space between the tracks, an adjustable counterweighted supporting member mounted upon and at a point substantially vertically above 60 said nozzle, and movable in both horizontal and vertical planes relative to said column, and a spout dependently supported near opposite ends from said supporting member and adjustable therewith to varying positions, the inlet end of said spout telescoping loosely over said nozzle and being movable relative thereto. 65
10. A locomotive water column comprising a substantially vertical stationary column to be mounted at the side of a railway track and provided with a valve actuating rod and a downwardly directed exit nozzle in a plane substantially parallel to the track relative to said column, a counterbalanced 70 supporting member pivotally mounted upon said column at a point substantially above said nozzle and movable in horizontal and vertical planes relative to said column, a spout telescoping at its inlet end freely over 75 said nozzle and dependently supported near opposite ends from said supporting member, and means carried by said supporting member to actuate said valve rod. 80
11. A locomotive water column comprising a substantially vertical stationary column to be mounted at the side of a railway track and provided with a valve actuating rod and a downwardly directed exit nozzle in a plane substantially parallel to the track 90 relative to said column, a counterbalanced supporting member pivotally mounted upon said column at a point substantially above said nozzle and movable in horizontal and vertical planes relative to said column, a 95 spout telescoping at its inlet end freely over said nozzle and dependently supported near opposite ends from said supporting member, and means to return and normally hold said spout and supporting member in an idle position out of the way of passing trains. 100

In testimony whereof I have affixed my signature in the presence of two witnesses.

C. W. MILES.

It is hereby certified that in Letters Patent No. 1,177,512, granted March 28, 1916, upon the application of Wallace M. Gray, of Cincinnati, Ohio, for an improvement in "Locomotive Water-Columns," errors appear in the printed specification requiring correction as follows: Page 2, line 6, for the word "ber" read *bar*; page 3, line 48, claim 8, for the word "and" read *end*; and that the said Letters Patent should be read with these corrections therein that the same may conform to the record of the case in the Patent Office.

Signed and sealed this 18th day of April, A. D., 1916.

[SEAL.]

R. F. WHITEHEAD,

Acting Commissioner of Patents.
